UNITED STATES PATENT OFFICE.

DANIEL G. LILLEY, OF DENVER, COLORADO.

AEROPLANE CONTROL.

Application filed November 25, 1927. Serial No. 235,539.

This invention relates to improvements in aeroplanes and has reference more particularly to improvements in the control mechanism.

5 It is well known that aeroplanes constructed in the usual manner have considerable difficulty in rising from the ground under full load. It is evident that the vertical control elevator which is secured to the tail of the plane is of very little, if any, assistance in getting the plane into the air and that it is therefore necessary to impart to the plane such a speed that the reaction between the air and the wing surfaces will 10 raise the plane off from the ground.

15 After the planes are in the air, the steering is done entirely by means of rudders and elevators secured to the tail of the plane and as this is analogous to steering an automobile by the rear wheels, it is evident that the proper control of an aeroplane is a feat that requires a great amount of experience.

20 It is an object of this invention to provide aeroplanes with elevators that are secured to the nose of the plane and which can be adjusted by the same mechanism that controls the elevator on the tail of the plane so that at least a portion of the control is effected from the front end, thereby making 25 the steering easier. Another advantage of having elevators near the front is that they can be placed directly behind the propellers and will therefore be subjected to the action of an air current of high velocity that makes 30 them very effective. Elevators of this type hinged so as to be movable about a horizontal axis are of great help in getting the plane into the air in starting, for reasons 35 that will be hereinafter more fully explained.

40 When an aeroplane is provided with pontoons that project below the plane, a considerable distance, or with any other type of landing gear, the inertia and the resistance offered by the landing gear when the 45 plane is started tends to tip the nose of the plane downward and prevents the plane from gaining elevation easily. By the simple expedient of providing an elevator 50 across the nose of the plane and adjusting its angular position, it is possible to produce a force that counteracts the resistance and inertia effect of the landing gear and thus make it easier to get into the air.

When a plane is in flight, it often happens 55 that it becomes subjected to strong air currents that produce a downward pressure on the upper wing surfaces and this forces the plane downwardly. When a plane is provided with elevators at the rear only, it 60 often happens that there is a considerable loss of elevation before the plane can be adjusted so as to get the plane back to its proper elevation. By attaching an elevator to the nose of the plane and operating this 65 in cooperation with the rear elevator, it is possible to quickly overcome this downward pressure and to prevent the drop in elevation as the front elevator working in conjunction with the rear elevator produces a 70 torque couple that tends to rotate the plane about a transverse axis passing through its center of gravity.

75 When a plane is provided with three engines, one is usually located at the very tip of the fuselage and one on each side, the latter being carried by the wings. In such planes an auxiliary elevator may be located directly to the rear of each engine. In tandem planes, such as have been proposed for 80 transoceanic service, the engines are carried by wings on each side of the fuselage and an elevator is provided to the rear of each propeller. An elevator may also be provided near the nose of the fuselage and this may 85 then be of considerable size so as to function as a wing during normal flight.

90 In order to more clearly describe my invention, reference will now be had to the accompanying drawings in which the preferred embodiments of the same have been 95 illustrated, and in which:

Fig. 1 is a plan view of an aeroplane constructed in accordance with my invention, portions being broken away to better disclose the construction;

Fig. 2 is a transverse section taken on line 2—2, Fig. 1;

Fig. 3 is a section taken on line 3—3, Fig. 1, and shows a portion of the control mechanism for the elevators;

Fig. 4 is a section taken on line 4—4, Fig. 2;

Fig. 5 is a view looking in the direction of arrows 5—5, Fig. 4, and shows the control lever for the elevators located underneath the wings;

Fig. 6 is a view, partly in section, taken

on line 6—6, Fig. 4, and shows the control lever for the rudder and for the front and rear elevators;

Fig. 7 is a section taken on line 7—7,
5 Fig. 4;

Fig. 8 is a section taken on line 8—8,
Fig. 1;

Fig. 9 is a diagrammatic representation
of the rudder control; and

10 Fig. 10 is a view showing my invention
applied to a multiple tandem wing aero-
plane.

In the drawings numeral 1 is the fuselage
15 of an aeroplane and 2 the wing. A pro-
peller 3 is secured to the nose of the fuselage
and operated by an engine in the usual man-
ner. In the plane illustrated, I have shown
20 three propellers which have all been desig-
nated by the same reference numeral, two of
25 these propellers are supported from the
wings in the manner indicated. In the ordi-
nary aeroplanes, a rudder 4 and an elevator
5 are provided at the rear end of the fuse-
lager and these are controlled by a suitable
30 apparatus. As indicated above, it is the
object of this invention to provide the aero-
planes with elevators and rudders at the
front as well as at the rear, and in Fig. 1
I have shown a rudder 4^a that is secured to
35 the tip of the fuselage and also two auxil-
iary elevators 5^a that are also secured to
the front end of the fuselage directly be-
hind the propeller. The elevators 5^a are
hinged to a transverse piece 6 so that they
40 may be pivoted about the axis of the hinge
7. I have also provided mechanism, which
will be shortly described, that interconnects
the elevators 5 and 5^a and the rudders 4 and
4^a so that they will operate together. In
45 the embodiment illustrated in Fig. 1 I have
also shown elevators 8 that are located di-
rectly behind the propellers which are car-
ried by the wings. These elevators are
hinged at 9 to the brackets 10 that extend
50 downwardly from the underside of the
wings in the manner shown most clearly
in Fig. 8. Secured to the wings to the rear
of the elevators 8 are downwardly extending
brackets 11 in which the shaft 12 is jour-
55 nalled. Shaft 12 is provided with a plu-
rality of arms 13 whose ends are provided
with longitudinal slots 14 for the reception
of pins 15 that are connected to the rear
edges of the elevators. When shaft 12 is
60 rotated, the inclination of elevators 8 can be
altered to any extent desired between the
limits indicated by the full line and the
dotted line position, in Fig. 8. I have also
indicated by dotted lines in Fig. 8, a con-
65 struction in which a plurality of elevators
can be employed, if desired. For the pur-
pose of rotating shaft 12, I have provided a
lever 16, Figs. 4 and 5, one end of which is
provided with a pawl 17 that cooperates
65 with notches 18 in the quadrant 19 that is

secured to the roof 20 of the fuselage. A
lever or handle 21 controls the pawl 17 in
the usual manner. The pilot which is so
seated that lever 16 is accessible at all times,
can adjust the position of elevators 8 by
means of lever 16 and keep them in adjusted
position as long as may be desired.

For the purpose of controlling the eleva-
tors 5 and 5^a and the rudders 4 and 4^a, I
have provided a mechanism which I will now
describe. Referring now more particularly
to Figs. 4, 6, 7 and 9, it will be observed that
I have provided a plurality of bearings 22
that are secured to the bottom or floor 23 of
the fuselage. Mounted for rotation in these
bearings is a shaft 24. This shaft has an off-
set flat, substantially circular part 25 that is
located between the two central bearings. A
plate 26 of similar shape and size as the part
25 is secured to the shaft by means of bolts
27 in the manner shown in Fig. 7. A lever
commonly known as the joy stick and which
has been indicated by numeral 28, extends
between the parts 25 and 26 and is pivoted
to these by means of a bolt 29. It is evident
that lever 28 can be moved to the right or
left, (Fig. 4) about its pivot 29, without ro-
tating the shaft 24, but if the motion is in a
plane that crosses shaft 24, the latter will be
rotated. Secured to the outer ends of shaft 24
are arms 30. The upper ends of these
arms carry pins 31 that extend through the
slots 32 in levers 33. Levers 33 are pivotally
attached to the shaft 12 so that they may be
rotated about the latter. Flexible steel wire
cables 34 are secured to the levers 33 at
points equidistant from the axis of shaft 12,
Fig. 2. One end of these cables is secured to
the T-shaped lever 35. These levers are
pivoted at 36 and have a laterally extending
arm 37 which is provided with an elongated
slot 38 for the reception of a pin 39 that is
secured to the rear edge of the elevators 5^a.
The other ends of cables 34 are secured to the
ends of the lever 40 that is rigidly secured to
the elevator 5 in the manner shown in Fig.
3. It is now evident that if lever 28 is
moved so as to rotate the shaft 24, that the
front and the rear elevators will be moved
simultaneously in such a direction that their
joint action will tend to rotate the plane
about an axis that passes through the center
of gravity. It is also evident that the ele-
vating force of the front elevator will be
very great in comparison with the area of the
elevator as these elevators are located di-
rectly behind the propeller, and therefore
subjected to an air blast of very high ve-
locity.

Attention is called at this point to the fact
that a stationary plane 41 is located directly
to the front of elevator 5, Fig. 3. These sta-
tionary planes help to stabilize the action of
the elevator. Similar stationary members 6
are located to the front of the elevators 5^a.

The rudders 4 and 4^a are operated by a sidewise motion of the lever 28. In order to better explain this operation attention will be first called to Fig. 6 from which it will be observed that the lower end of lever 28 is provided with an arcuate slot 42 through which the bar 43 extends. This bar has downwardly projecting pins 44 one of which is located on each side of the lower end of lever 28. With this construction lever 28 can be rotated about the axis of shaft 24 without disturbing in the least the position of bar 43. But if lever 28 is moved sidewise so that it will rotate about the pivot 29, rod 43 will be moved in one direction or the other, depending upon the movement of the lever. Referring now more particularly to Fig. 9, it will be observed that the ends of bar 43 are connected to the outer ends of arms 45 of the bell crank levers that are pivoted at 46. The other arms 47 of these bell crank levers are attached to the cables 48. These cables have their rear ends connected at 49 to the ends of the transverse lever 50 which is attached to the rear rudder 4. To the front of the bell cranks the cables extend around the pulleys 51 and are attached to the movable end of the front rudder 4^a. If lever 28 is moved so as to bring the lower portion into the dotted line position shown in Fig. 9, the front and rear rudders will be moved to the dotted line position and if the lever is moved in the opposite direction, the rudders will of course be moved in the opposite direction. The motion of the plane towards the right or left is controlled by a corresponding movement of the control lever. While the up and down motion of the plane is controlled by the same lever moving about the axis of shaft 24. As lever 28 can move simultaneously about two rectangularly related axes a compound movement can be obtained which will simultaneously operate both the elevators and the rudders to the extent required. Attention is called, however, to the fact that the elevators and the rudders can be operated entirely independent of each other.

Let us now consider the operation of a plane constructed in accordance with my invention. When the plane is to take off from the ground, the operator will adjust the positions of the elevators 8 by means of handle 16 so that these will incline downwardly and rearwardly and therefore have a greater angle of incidence than during normal flight. The operator may, at the same time, adjust the elevators 5 in a corresponding manner. When the propellers are in operation, the strong air currents thus produced will cooperate with the elevators 8 and 5^a and produce a force that tends to raise the front end of the aeroplane from the ground. As these elevating forces are greatly increased by means of the action of the elevators that

are located underneath the wings and to the front of the wings, the aeroplane will be raised off of the ground sooner than it would be if these elevators were not present, and this makes it possible to get into the air 70 quicker and with a larger load than would be possible if the planes were constructed without these elevators. As soon as the aeroplane is in flight, the pilot may adjust the position of the elevators 8 so as to reduce 75 the angle of incidence to any degree desired.

In Fig. 10 I have shown a tandem wing aeroplane of the type that has been proposed for use in transoceanic flights. These aeroplanes differ from the one shown in Fig. 1 principally in this, that they are provided with a plurality of wings arranged in tandem and that each wing is provided with at least two engines and propellers, some of the wings may even be provided 85 with four engines and four propellers like the central wing in Fig. 10. Such aeroplanes may be equipped with elevators analogous to those already described and operated in the same manner. The elevators 90 that are located underneath the wings are preferably mounted so that each set in each wing may be controlled independently of the set in the other wings so that it is possible to use them to keep the aeroplane on 95 an even keel and to stabilize it during flight, as well as to assist the aeroplane in going through the air.

I desire to call particular attention to the combined front and rear elevators which 100 are connected so as to move in synchronism with each other and which impart to the aeroplane two forces in opposite directions that form a torque couple whose moment tends to rotate the aeroplane about a horizontal axis passing through its center of gravity. 105

In the specification and claims I have referred to an axis passing through the center of gravity. I want it understood, however, that this axis does not necessarily have to pass through the actual center of gravity, but this expression is used in describing the axis about which the plane is rotated during the movement imparted to it by the elevators or the rudders and is believed to coincide quite closely with the center of gravity. 110

A plane in flight with the wings at such an angle that strong winds are brought to 120 bear upon the upper surface, results in loss in elevation. Where such winds are sufficiently strong the plane may be forced down rapidly, or at least with considerable loss in elevation before the tail can be maneuvered into a position whereby the propellers can again start the plane upward. If the engines are speeded up before the plane is in position pointing upwardly, the increased speed will merely force the plane 125 130

lower. As intimated above, this difficulty can be overcome by the use of a nose elevator and rudder in cooperation with a tail elevator and rudder, thus providing means to force a plane to be instantly pivoted about a point known as the center of gravity of the plane. The plane being pivoted on this axis at the will of the pilot so as to cause the winds to be exerted upon the under surface of the wings instead of the top surface, which will immediately enable the propellers to force the plane upward, without any loss in elevation. Such a plane well constructed and amply powered will have little to fear from any ordinary storm conditions. Under ordinary flying conditions, only slight movement of the joy stick should be necessary to properly control the plane, by reason of the cooperative incidence given the nose and tail elevators and rudders, which would leave the pilot still with a wide range of control at his disposal over and above that required for ordinary flying conditions, to be used in any emergency. Even though the nose elevators and rudder were to be given only very slight incidence, the action of the nose propeller upon them should enable the pilot to control his plane with fine precision. Although the above invention has been described in connection with heavier than air machines, it is obvious that this invention can also be used in connection with lighter than air machines.

35 In the specification and the claims I em-

ploy the term "horizontal axis". By this term it is my intention to define an axis that is parallel with the plane of the wings and with the axes about which the elevators are pivoted, and therefore in actual flight this axis may be inclined with respect to the plane of the horizon. The rudders naturally operate to rotate the plane about an axis perpendicular to the horizontal axis as above defined. 45

Having described the invention what is claimed as new is:

1. In an airship having a plurality of wings and a plurality of propellers, an elevator located directly to the rear of each 50 propeller, another elevator located at the rear end of the airship, means for simultaneously operating the last named elevator and one of the first named elevators and means for operating the other elevators independently. 55

2. An airship having a fuselage, wings and propellers, one propeller located at the front end of the fuselage and one on each side, an elevator located to the rear of each 60 propeller, an elevator located at the rear end of the fuselage, means for interconnecting the elevators at the front and the rear of the fuselage so that they may be operated together and means for controlling the elevators that are located on the sides of the fuselage. 65

In testimony whereof I affix my signature.

DANIEL G. LILLEY.
